JAMES LINNARD, OF PHILADELPHIA, PENNSYLVANIA, ASSIGNOR TO HIMSELF, FRANCIS D. WORLEY, AND WILLIAM S. HASSELL, OF SAME PLACE.

Letters Patent No. 90,278, dated May 18, 1869.

IMPROVEMENT IN SAFETY-VALVES.

The Schedule referred to in these Letters Patent and making part of the same.

To all whom it may concern:

Be it known that I, JAMES LINNARD, of Philadelphia, Pennsylvania, have invented an Improvement in Safety-Valves; and I do hereby declare the following to be a full, clear, and exact description of the same.

My invention consists of a safety-valve for steam-boilers, constructed and operating as fully described hereafter, in such a manner that it cannot be overloaded nor tampered with to a dangerous extent by unauthorized persons.

In order to enable others skilled in the art to make and use my invention, I will now proceed to describe its construction and operation, reference being had to the accompanying drawing, which forms a part of this specification, and in which—

Figure 1 is a vertical sectional view of my improved safety-valve for steam-boilers;

Figure 2, a transverse vertical section of the same, on the line 1-2, fig. 1;

Figure 3, a sectional plan view on the line 3-4, fig. 1; and

Figure 4, a perspective view, illustrating a modification of my invention.

Similar letters refer to similar parts throughout the several views.

A represents the cast-iron base of the valve, which is secured to a steam-boiler in the usual manner, and extending vertically through this base is a cylindrical opening, a, having at its upper end a seat, a', upon which rests the valve B.

Upon the top of the valve B, and retained laterally between lugs c c' on the same, rests an elliptic or other suitable spring, D, upon which is caused to bear a set-screw F, passing through a threaded opening in a yoke, G, the latter being attached, at its opposite ends, to standards H and H', which are firmly secured to the base A.

Links d d, which are hung to the lugs c of the valve, serve to connect the latter to a lever, J, which is pivoted at a point, f, to an extension of the standard H'.

The lever J is constructed with an opening in the centre, as best observed in fig. 3, so that it may pass over the set-screw F and on each side of the yoke G, and the extremity of this lever rests upon the short

arm of a lever, M, which is hung to the standard H, and is provided at the outer end with a suitable handle, i.

The projecting arm of the operating lever M passes through a slot, j, in a thin metal casing, P, which is bolted, or otherwise secured, to the body A of the valve, and is provided with an escape-pipe, q.

Before securing the casing P to the base of the valve, and thus covering the parts above the same, the set-screw F is so operated as to cause the spring D to bear upon the valve with the requisite degree of pressure, which is determined by means of the steam-gauge.

When the casing P has been properly secured in its place, nothing will project beyond the same, except a portion of the operating lever M, by depressing which the valve B may be raised from its seat, through the medium of the lever J and links d d.

When the valve is thus closed in, and protected by the casing P, it cannot be loaded beyond the point first determined, or tampered with to a dangerous extent by unauthorized persons, the only result caused by the manipulation of the lever M being the lifting of the valve and a harmless blowing off of steam, which, after passing into the casing, would escape through the pipe q.

In place of the lever M, a spindle, passing through a packed bearing, and provided at its inner end with a cam, or other device, for operating the lever J, may be employed. (See fig. 4.)

I claim as my invention, and desire to secure by Letters Patent—

1. The combination of the lever J, valve B, and links connecting the lever to the valve, substantially as herein described.

2. The combination of the lever J, valve B, spring D, and links d d, when arranged in respect to the lever M, or its equivalent, substantially as specified.

In testimony whereof, I have signed my name to this specification, in the presence of two subscribing witnesses.

JAMES LINNARD.
